BRAZELTON T. BROWN, OF INDIANAPOLIS, INDIANA, ASSIGNOR OF ONE-HALF TO
THOMAS H. KOMSTOHK, OF INDIANAPOLIS, INDIANA.

PATTERN MECHANISM FOR CASTINGS.

Application filed November 25, 1921. Serial No. 517,702.

To all whom it may concern:

Be it known that I, BRAZELTON T. BROWN, a citizen of the United States, and a resident of Indianapolis, county of Marion and 5 State of Indiana, have invented a certain new and useful Pattern Mechanism for Castings; and I do hereby declare that the following is a full, clear, and exact description thereof, reference being had to 10 the accompanying drawings, in which like numerals refer to like parts.

This invention relates to a pattern for castings, and more particularly for that 15 type of castings surrounded by projections, such as an annular body having projections about the periphery thereof, or extending inwardly therefrom.

Heretofore it has been difficult to cast bodies, and especially annular bodies having 20 projecting portions surrounding them, for the reason that after the sand is packed about the pattern, the pattern cannot be withdrawn therefrom, because of said projections. This invention contemplates the 25 construction of a pattern of this type in which the projecting portions are movably mounted upon the main body of the pattern, whereby they may be raised and lowered by means of a suitable tool. With this arrangement 30 the projections may be lowered into the body of the pattern by applying a tool to the outer end thereof after the shape thereof has been impressed in the sand. Said projections having been thus removed 35 from interference with the sand, said pattern may be readily withdrawn therefrom in the usual manner.

The particular pattern shown and described herein is constructed for use in 40 casting a pulley having V-shaped projections extending transversely thereof with the vertex of each projection positioned centrally between the ends of the pulley. It will be quite apparent that a pattern of this type 45 cannot be withdrawn from the sand wherein the projections are rigidly mounted thereon. Therefore, said projections are arranged to be movable with respect to the main body of the pattern so as to be withdrawn radially within the surface of the 50 body portion, so as to permit its ready removal from the sand.

The full nature of the invention will be

understood from the accompanying drawings and the following description and 55 claims:

In the drawings, Fig. 1 is a front elevation of the pulley, with one movable projection removed. Fig. 2 is an end elevation having a portion of the end broken away, 60 and the projections drawn in the body portion. Fig. 3 is the same as Fig. 2 showing the projections in outwardly extended position. Fig. 4 is a section taken on the line 4—4 of Fig. 2. Fig. 5 is a section taken 65 on the line 5—5 of Fig. 3. Fig. 6 is an end elevation of a modified form with a portion broken away, showing internally extending gear teeth. Fig. 7 is a section taken on the line 7—7 of Fig. 6. 70

In the drawings there is shown a pulley having a body portion 10 cylindrical in shape which is rigidly secured upon the hub 11. Said hub is provided on each end with bearing members 12 which support 75 an annular drum 13 carried upon the spindles 14 extending into said bearings. Said drum is adapted to revolve within the hub 11 and be turned therein by a tool engaging the slot 15 in the end of one of the 80 spindles 14.

The body portion 10 is provided with a plurality of recessed grooves 16 of the same configuration as the projections to be cast on the finished product. As shown herein 85 the grooves 16 extend inwardly from each end of the body portion, meeting at the center so as to form a V-shaped groove curved about the periphery of a cylindrically-shaped body. Mounted in the grooves 90 16 so as to make a snug fit therein, there are movable projecting members 17 adapted to fit within said grooves so that their respective surfaces are flush when said projecting member is withdrawn therein. 95

Slidably mounted within the hub 11, and extending radially from the center thereof, there are a plurality of supporting posts 18 which project through a suitable opening in the body portion 10 into the grooves 100 16. As shown herein, there is a pair of such radially extending posts for each groove, as shown in Fig. 1. The projecting members 17 are rigidly secured to the outer ends of said posts by means of the screws 105 19, so as to be carried thereon. Pivoted

upon each end of the drum 13, spaced about the periphery thereof so as to extend radially therefrom at spaced intervals, there are a plurality of links 20 which extend through 5 suitable openings in the hub 11 and are pivoted at their outer ends to the posts 18, as shown in Fig. 4, there being provided in sufficient room in the opening through the body portion 10 to allow for the free move- 10 ment of said links therein adjacent the posts 18. The links 20 are so arranged that upon the drum 13 being turned slightly in one direction by a suitable tool engaging the outer end of the spindle 14, the links 15 will be moved in alignment with the posts 18. In this position said posts will be moved radially outward, carrying the projecting members 17 radially outward from the cylindrical surface of the body portion 20 so as to extend therefrom, as shown in Fig. 3. When turned in the opposite direction, the drum 13 will cause said links to move out of alignment with the posts 18, causing them to be drawn inwardly and with- 25 draw the projecting members 17 into the recesses 16, so that the surface of the members 17 and the body portion 10 will be flush.

When it is desired to cast a body having 30 irregularly or angularly disposed projections thereon, the pattern is made embodying the above described mechanism for extending and withdrawing the projections relative to the surface thereof. Said pro- 35 jections are extended as above described when placed in the sand, and after the sand has been properly molded thereon, said pro- jecti- 40 on- 10 ready removal of the pattern from the sand.

As shown in Fig. 6, the same principle may be employed for casting a large number of internal teeth of small pitch, wherein it is impractical to provide a pair of posts 45 for each tooth. In this construction the body portion 10 is provided with a plurality of openings 30 into which the teeth 31 may be withdrawn outwardly for presenting a smooth internal surface. The teeth 31 are 50 provided with substantial base portions 32 which fit snugly within the openings 30 when in extended position for guiding the tooth in its radial movement and maintaining it securely in its projecting position. 55 The base portions 32 are integral with the toothed portion 31, and are slidably mounted upon the spring metal plates 33 and 34 by means of the rivets 35 extending into said supporting members through short 60 slots in said plates. Said plates are arranged with respect to each other so as to permit of the expansion and contraction necessary for the different positions in which said plates are moved radially from the center. Said plates are slidably secured

on the ends of the posts 18 which move within the housing 36, and are moved radially therethrough by the links 20, as above described. By means of this arrangement with comparatively few posts and links, a 70 large number of teeth may be formed upon the pattern. When the links are moved in alignment with said posts, the plates are forced outwardly; and being formed of spring metal and slidably mounted with 75 respect to said posts and each other, their circumference may be contracted and the teeth 31 moved into projecting position for making a casting. Upon moving the links in the opposite direction, said plates are 80 expanded to their normal position and said teeth are pulled inwardly, so that the pattern will present a smooth internal surface which may be readily removed from the sand. This construction may also be em- 85 ployed in a like manner for operating a large number of external teeth or projec- tions.

It will be obvious that other means may be used for simultaneously moving the teeth 90 or projections in and out of the body of the pattern, such as a plurality of cam members employed in place of the links 20.

The invention claimed is:

1. A pattern for making annular castings 95 having a plurality of radial openings in the body thereof, projecting members mounted on said pattern and slidably in said openings, inwardly and radially extending posts secured to said members and radially slid- 100 able within said pattern, a rotatable member mounted within said pattern and a plurality of links pivotally connected with said ro- tating member and links to force the posts whereby the rotation of said member will 105 cause said post to slide inwardly and out- wardly radially of said pattern for causing said projecting members to be extended ra- dially therefrom or withdrawn radially 110 therein.

2. A pattern for making annular castings having a plurality of radial openings there- in, projecting members mounted in said pat- tern and adapted to slide inwardly and out- 115 wardly through said openings, a plurality of posts pivoted to said members and adapt- ed to slide radially within said pattern for causing said projecting members to be forced radially inwardly and outwardly with respect thereto, a rotating drum 120 mounted centrally within said pattern and provided with a shaft supported in suitable bearings therein, and a plurality of links pivotally mounted at one end to said drum and at the other end to said sliding posts for 125 causing said post and projecting members to slide in and out of said pattern upon the rotation of said drum.

3. A pattern for making castings having irregular or angularly disposed projections 130

about the surface thereof, projecting members mounted on said pattern, a rotatable member within said pattern, supporting posts secured to said projecting members, and a plurality of links pivotally connected to said rotating member and posts for causing said projecting members to extend from

said pattern when said rotary member is rotated in one direction, and be withdrawn within said pattern when rotated in the opposite direction.

In witness whereof, I have hereunto affixed my signature.

BRAZELTON T. BROWN.
